UNITED STATES PATENT OFFICE.

CHARLES B. CRABTREE, OF MANCHESTER, ILLINOIS.

MAIL-CARRIER.

No. 890,026.

Specification of Letters Patent.

Patented June 9, 1908.

Application filed October 2, 1906. Serial No. 337,110.

To all whom it may concern:

Be it known that I, CHARLES B. CRABTREE, a citizen of the United States, residing at Manchester, in the county of Scott and State of Illinois, have invented a new and useful Improvement in Mail-Carriers, of which the following is a specification.

This invention relates to a device designed to automatically distribute and collect mail, especially in rural districts, taking the place of the present rural delivery made by carriers employed for that purpose.

The invention consists of an elevated mail car, traveling upon elevated cables and driven by a small electric motor, the car being provided with suitable trolleys; and of receiving and delivery stations placed along the route and adapted to receive mail from the car and to deliver mail to the car, such exchange being made automatically as the car passes these stations.

The invention also consists in a special construction of trolleys and reversing mechanism whereby the car is automatically reversed and started upon its return trip when it has reached the end of the line.

In the drawings forming a part of this specification:—Figure 1 is a side elevation of a car and of one of the stations, the parts being shown in position to deliver and receive mail. Fig. 2 is a longitudinal section through the car, certain portions of the station being broken away, shown in section, or shown in dotted lines. Fig. 3 is a section on the line 3—3 of Fig. 1. Fig. 4 is a detail perspective view of one of the stations, the parts being shown in their normal positions, certain parts being out of proportion to more clearly bring out details of construction. Fig. 5 is a section on the line 5—5 of Fig. 2. Fig. 6 is an irregular section on the line 6—6 of Fig. 2. Fig. 7 is a detail perspective view showing a portion of the under side of the car. Fig. 8 is a side elevation of an end post showing a buffer attached thereto. Fig. 9 is a detail perspective view of a bracket for holding certain tripping mechanism, a portion of said mechanism being shown in dotted lines.

In these drawings 1 represents a trolley wire, and 2 represents my car. This car is divided by a horizontal partition into upper and lower compartments. The top of the car has a central sunken portion as shown at 4, which forms a receptacle for receiving mail matter. Vertical partitions 5, extend between the bottom of the car and the horizon-

tal partitions 3, and divide the lower portion of the car into a plurality of boxes, which boxes equal in number, the number of delivery stations and receiving stations, on the car route. The bottoms 6, of these boxes are hinged to swing downwardly. To support the car, I provide a track formed preferably of two parallel cables 7, arranged below and parallel to the trolley wire 1. The top of the car is provided with brackets 8, which overhang the wire 1, and grooved wheels 9, are secured in these brackets and travel upon the wire 1. Brackets 10, are secured to the bottom of the car and grooved wheels 11, travel upon the wires 7, and support and guide the car. A suitable motor 12, of any desired description so long as it is reversible is placed in the car and a trolley pole 13 is arranged longitudinally in the upper compartment of the car where it is supported pivotally at a point near its center of gravity. This trolley pole projects from the car from the ends and carries two uprights 14 and 16, which are provided with trolley wheels 15 and 17, and as the pole 13, is not evenly balanced one of these wheels is always off the wire.

At what will be termed the front end of the car, the pole 13, is extended forwardly and upwardly as shown at 13^a. A suitable conducting wire 18 leads from the pivotal point of the pole 13 through a suitable reverse mechanism and to the motor 12. A reversing lever 20, is connected by a link 21, to the pole 13. Suitable letter drops 22, are formed in the sides of the car through which letters may be deposited into the various boxes. As the stations are all alike a description of one of them, will be sufficient. A U-shaped frame 23, is provided with laterally extending arms 24, which arms are provided with upwardly extending shoes 25, which shoes support the wires 1 and 7 respectively. A receptacle 26, to receive the mail matter, is arranged between the side members of the frame 23 and below the wires 7. This receptacle is provided with a sliding top 27, and upon one side of the receptacle 26 is pivoted a lever 28 which at its lower end carries a ball weight 29, which normally holds the lever in a vertical position. A pivoted link 30 pivotally connects the lever 28 with the sliding lid 27 so that when the lever 28, is thrown out of vertical position in one direction the lid will be moved into open position.

Upon one side of the car is secured a long bar the front end of which is curved upwardly as shown at 32. This bar strikes the lever 28, and swings it from a vertical position 5 into the position shown in Fig. 1 thereby opening the lid 27 of the receptacle 26. The hinged bottoms 6, are cut out on the side opposite the hinges as shown at 6^a and to the partitions 5 are secured springs 33, the free 10 ends of which extend downwardly and form hook members which engage the notched portions of the bottoms 6 and lock the said bottoms in their normal positions. To each of these springs 33, is secured a finger 34, 15 which projects laterally beyond a side of the car and levers 35, are pivoted to the said side of the car, one lever being adjacent to each of said fingers. These levers are off-set adjacent their lower ends and this off-set 20 varies so that the lower ends of these levers are out of alinement with each other. Upon the receptacle 26, is mounted a trigger 36, which is in position to be struck by the lower end of one and only one of the levers 25 35. Upon the frame 23, is secured a bracket or frame 37, in which is pivotally held a mail box 38. A bracket 39, is secured to a side member of the frame 23, and in this bracket is journaled a rotatable angled rod 40, the 30 angled portion of which extends under the mail box 38, and normally holds the same in the horizontal position as shown in Fig. 4. The lower end of this rod is provided with an arm 41, which at its free end carries a roller 35 42, and this arm is held normally in engagement with a finger 43, of the bracket 39, by means of a spring 43^a. The brackets 10, have shafts 44 journaled in them on which the rollers 11, are mounted and upon one of 40 these shafts, is also mounted a gear wheel 45, which meshes with a gear wheel 46, mounted on the armature of the motor, and upon the other end of the armature shaft is mounted a pulley 47 and a belt 48 runs to a pulley 49, held upon the lower end of a vertical shaft 45 50, which is loosely mounted in a bracket 51, and which carries at its upper end a ball governor 52, of the usual type.

A bifurcated lever 53, is pivoted within 50 the car and its bifurcated end portions carry brake shoes 34, which bear upon rollers 55, mounted upon one of the shafts 11. The lower end of the shaft 50, bears upon a suitable socket 57, formed upon the lever 53, 55 and the weight of the shaft holds the shoes 54, in engagement with the rollers 55, it being understood that the amount of pressure exerted upon the brake lever 53, by the shaft will depend upon the action of the governor 52. At the end of the route to the post 60, is secured a V-shaped buffer 61. The front end of the car there is a forwardly projecting post 63, which post carries downwardly extending jaws 64, normally drawn together 65 by a spring 65. These jaws are in a position

to receive and grip the forward end portion of the trolley pole 13 when its front portion 13^a, has struck and rides up, upon the buffer 61, and the spring 65, holds the jaws in a closed position after they have been forced 70 open by the pole 13, and have gripped the same.

The operation of the device is briefly, as follows:—Mail to be distributed is placed in the boxes by means of the drops 22, and the 75 car is then started from the post office end of its route. As it reaches the various stations the bottoms 6, will be, each, automatically tripped and will fall open at the proper stations and the covers of the receptacles 26, 80 will be opened and all mail matter of the boxes will be deposited within the receptacle 26.

It will be obvious from what has already been stated that only one box 6, will be 85 opened at each station as the opening of each box and dropping of the mail contained therein, depends upon the trigger 36, coming into contact with one of the levers 35 and the trigger placed upon the receptacle 26, intended to receive the mail of John L. Dough, 90 will only engage the lever 35, which trips the bottom 6, of the box in which John L. Dough's mail has been placed, and mail contained in the other boxes will not be dropped 95 into the receptacle intended for the mail of the said John L. Dough.

As heretofore explained, the cover 27, of the receptacle is automatically opened, by the lever 28, coming into contact with the bar 31 carried by the said lever which forces the said lever into the position shown in Fig. 1. It will be obvious that when the end 32 of the bar 31, strikes the upright lever 28, and commences to throw the same into 105 an inclined position, thereby lifting the weight 29 and sliding the cover 27, that the speed of the car will be momentarily checked. The effect of this action upon the governor 52, will be to permit the shaft 50, to move 110 downwardly and in fact it will be forced downward by the action of the governor. This will increase the pressure of the shaft upon the lever 53, and the brake shoes 54, will be applied to the wheels 55, which wheels are 115 fixed to a shaft 11 and this shaft carries the gear wheel 45 also fixed upon the shaft and meshing with the gear wheel 46 fixed to the armature shaft. The action of this brake tends to slacken the speed of the car slightly and therefore allows ample time for the delivery of the mail. After the car has passed the station, it will gradually pick up its normal speed and as such speed is gained, the action of the governor will lift the shaft 50, and the pressure 120 on the brake shoes will be removed. At the same time that mail is delivered the bar 31, will strike the rollers 42, and will throw the arm 41, outwardly against the tension of the spring 43^a thereby rotating the angled rod 125 130

40, throwing its upper angled end portion out from under the pivoted box 38 and the mail deposited therein will be dropped into the receptacle 4, formed by the depression in the 5 top of the car. To protect this mail from the weather it is obvious that it can be placed in a small oil skin bag; or it can be placed in a tin or other water proof box, and the box or bag placed in the box 38 and dropped from 10 the same when the box 38 is tripped.

When the car reaches the end of the route the part 13^a of the pivoted trolley bar 13, rides up upon the shoe and lifts the trolley wheel 15, from the wire. The trolley bar 13 15 is held in this new position by the spring actuated grip or clamp 64, and the trolley wheel 17, rests upon the wire 1. This change of the position of the part of the trolley bar 13, shifts the reversing lever 20, changing the 20 direction of the current through the motor, or through the field coils, according to the kind or style of motor employed and the car will be automatically reversed and will travel back again to its starting point.

25 I do not make any claim upon any particular kind of motor or upon any of the wiring for the said motor as any of the present systems of applying motive power by means of electricity may be employed.

30 Having thus fully described my invention, what I claim as new and desire to secure by Letters Patent, is:

1. In a device of the kind described, a car having compartments, means for discharging 35 mail from said compartments and means arranged adjacent the path of travel of the car for delivering mail thereto, the top of the car having a sunken portion to receive said mail.

2. An electrically propelled mail car, a 40 longitudinally arranged trolley pole pivoted off its center of gravity, uprights carried by said pole on opposite sides of the pivotal point, wheels carried by said uprights, said wheels alternately engaging a trolley line 45 wire, and means carried by the car for gripping and holding an end of the trolley pole at a predetermined point, to change the relative positions of the wheels and reverse direction of the car.

50 3. An automatic mail carrier comprising a

car, a reversible motor, a track for the car, a line wire, a trolley pole having its ends extending from the ends of the car, uprights carried by said projecting pole ends, trolley wheels on said uprights, the trolley pole being pivoted near its center of gravity, one trolley wheel being normally disengaged from the wire, means arranged at the end of the track for rocking the pole on its pivotal point and bringing the last mentioned trolley 55 wheel into engagement with the line wire, and means carried by the car for holding said wheel in engagement with the wire, and the other trolley wheel off of the wire.

4. A device of the kind described comprising an elevated carrier having a plurality of compartments therein, adapted to contain mail matter, a plurality of receptacles arranged below the path of travel of the car, a sliding cover for each of said receptacles, a 65 weighted lever, a link connecting said lever to the cover, means carried by the car, adapted to strike and throw said lever out of its normal position thereby opening a receptacle, and means for automatically discharging 70 into each of said receptacles mail matter from one of the said compartments of the car.

5. A device of the kind described comprising a car adapted to carry mail matter, a 80 receiving box arranged adjacent the car route, means carried by said receptacle for opening the same, and means carried by the car adapted to engage and operate said opening means, means for automatically delivering 85 mail from one of the boxes, into said receptacle, a pivoted box adapted to receive mail matter and suspended in a plane above that in which the car travels, means for normally holding the said pivoted box in a horizontal 90 position and means carried by the car adapted to strike said box holding means and release the box, thereby discharging mail matter from the box into the car, as the car passes beneath it.
